UNITED STATES PATENT OFFICE.

JOSEPH L. HORN AND JAMES QUINN, JR., OF DENVER, COLORADO; SAID QUINN ASSIGNOR TO SAID HORN.

COUPON CHECK-ENVELOP.

SPECIFICATION forming part of Letters Patent No. 639,983, dated December 26, 1899.

Application filed December 22, 1898. Serial No. 700,059. (No model.)

To all whom it may concern:

Be it known that we, JOSEPH L. HORN and JAMES QUINN, Jr., citizens of the United States, residing at Denver, in the county of 5 Arapahoe and State of Colorado, have invented a certain new and useful Improvement in a Coupon Check-Envelop, of which the following is a full, clear, and exact description of the invention, such as will enable 10 others skilled in the art to which it appertains to make and use the same, reference being had to the accompanying drawings, forming a part of this specification, in which similar letters of reference indicate corresponding 15 parts in all the figures.

Our invention relates to a class of envelops designed to be used by banks and financial institutions for transmitting coupons. They are made of a good grade of heavy paper or 20 any suitable material.

The objects of our invention are to provide an envelop about the size of an ordinary bank check or draft, which facilitates the handling of same among other items, one that provides 25 space for a complete record on the face, the bank endorsements to be made on the back the same as on an ordinary check or draft.

We refer now to the drawings in further explaining the nature and objects of our invention, in which—

Figure 1 is a plan view of the face of our invention having the end flap extended as it appears before sealing. Fig. 2 is a perspective view of our invention with the envelop or 35 pouch open to receive coupons. Fig. 3 is a view of the paper or material as cut preparatory to manufacturing the envelop.

A is the portion of the paper or other material used in manufacturing the invention 40 which forms the face of the envelop.

A' is the end flap of the envelop.

The dotted line B indicates the position the end flap occupies when sealed.

A² is one of the side flaps, which is folded 45 in manufacturing to the dotted-line position indicated by B³ in Fig. 3.

A³ is the side flap on the opposite side of

the cut form, Fig. 3, and is folded in manufacturing so as to lap over the edge of the flap A², as indicated by the dotted lines B³ in Fig. 50 3, when the two are glued or otherwise secured together.

The side flaps A² and A³ are provided with triangular ends A⁴ and A⁵, which when folded and glued to the extension end C of the main 55 portion A form the V-shaped reinforcement A⁶, as indicated by the dotted lines B' in the several figures. This reinforcement gives the extension end C about the same strength as the part of the main portion A where the envelop or pouch is formed. This means provides the requisite length and obviates the necessity of having a long envelop or pouch, as they are not practical, owing to the inconvenience of removing the coupons. It also 60 65 eliminates the necessity of attaching a counter-check or piece of paper to a small envelop, as is sometimes done by banks and financial institutions in handling coupons in the general business way.

We do not confine ourselves to any one manner of manufacturing our new envelop, but desire to cover the principle involved and vary the way of making it to suit the purposes for which it is designed.

Having thus described the nature and objects of our invention, with the manner of constructing the same, what we claim as new, and desire to secure by Letters Patent, is—

In a coupon check-envelop of the class described, comprising an extension end, the pouch or sack, having the side flaps extending out, glued to the extension end and designed to stiffen said extension, for the uses and purposes herein set forth and substantially as specified.

In testimony that we claim the foregoing as our own we hereunto subscribe our names in the presence of two witnesses.

JOSEPH L. HORN.
JAMES QUINN, JR.
